ATTORNEY

UNITED STATES PATENT OFFICE.

GUSTAV A. KRUTTSCHNITT, OF NEWARK, NEW JERSEY.

DESIGN FOR A SIGN-PLATE OR SIMILAR ARTICLE.

SPECIFICATION forming part of Design No. 31,628, dated October 10, 1899.

Application filed September 18, 1899. Serial No. 730,944. Term of patent 3½ years.

To all whom it may concern:

Be it known that I, GUSTAV A. KRUTTSCHNITT, a citizen of the United States, residing at Newark, in the county of Essex and State of New Jersey, have invented and produced a new and original Design for a Sign-Plate or Similar Article, of which the following is a specification, reference being had to the accompanying drawings, forming part thereof, and in which—

Figure 1 is a face view of a sign-plate bearing and incorporating my design, and Fig. 2 is an edge view of same.

The leading feature of my design consists of the border ornamentation along the outer portions of the face of the substantially flat plate, substantially as shown in the drawings.

In the drawings, A designates the plate,

which has a substantially flat face, as shown in Fig. 2, and which face, as illustrated in Fig. 1, bears the ornamental border comprising the main ornamental scroll-figure B and the inner defining border-line C. The scroll-figure B has the appearance of being in relief and as possessing a delicate mottled surface.

What I claim is—

The design for a sign-plate or similar article, substantially as shown and described.

Signed at New York, in the county and State of New York, this 16th day of September, A.D. 1899.

GUSTAV A. KRUTTSCHNITT.
